UNITED STATES PATENT OFFICE.

HORATIO N. HOUGHTON, OF HALIFAX, VERMONT.

IMPROVEMENT IN WINE AND CIDER PRESSES.

Specification forming part of Letters Patent No. 146,181, dated January 6, 1874; application filed December 9, 1873.

To all whom it may concern:

Be it known that I, HORATIO N. HOUGHTON, of Halifax, in the county of Windham and State of Vermont, have invented certain new and useful Improvements in Wine and Cider Presses; and I do hereby declare the following to be a full, clear, and exact description of the invention, such as will enable others skilled in the art to which it pertains to make and use it, reference being had to the accompanying drawings, which form part of this specification.

The nature of my invention relates to an improvement in wine and cider presses; and it consists in, first, the rod or bar to which the piston is secured, having a series of holes cut through it, in which are placed keys or pins, against which the movable head bears, to force the piston in and out; second, in the arrangement and combination of parts, which will be more fully described hereafter.

The accompanying drawings represent my invention.

Figure 1 is an end view of my press. Fig. 2 is a longitudinal vertical section of the same. Fig. 3 is a longitudinal section of the same.

a represents the base-plate, which is secured to the ground-sills *b* by means of screw-bolts *c*, which pass down through the horizontal and vertical timbers *d* *e*, which form the frame-work of the machine. To the inside of these timbers are secured a number of boards, *g*, which have been split a part of their length by a saw, or have a small space left between them, through which the juice flows, and which boards form the press-box. The end piece *h* is formed in the same manner, and is braced in position against the pressure of the piston by the frame *i*, which can be taken out laterally, so as to allow the end to be removed, to clear out the pomace after it has been pressed. Upon one end of the frame is journaled the screw-shaft *j*, which is made to revolve by any suitable means, and which gears with the two wheels *k*, secured to the ends of the two screws *l*. Moving back and

forth upon these screws, between the timbers *d* and guides *m*, is the head *n*, for operating the piston *o*. To this piston is secured the piston-rod *2*, which has a series of holes, *3*, cut its entire length, in which are placed keys or pins *4*, against which the movable head bears to force the piston against the pomace, or to draw it back again. After the pomace has been thoroughly pressed, and it is desired to clean it out of the box, the end piece *h* and *i* is removed, and the piston is forced forward until the entire mass is driven out through the end.

In packing the pomace into the box to be pressed, it is placed in sections between the two movable partitions *5*, which are held in grooves prepared for them in the sides of the box. After the partitions have been put in place, a layer or wall of straw is put in around the sides of the box and against one partition, so as to inclose the pomace, and thus form a straining-surface. After the section is formed, the rear partition is taken out and moved forward, so as to form a second section, and so on until the pomace has all been thus disposed of. The two partitions are then removed, the cover *6* put on top, and then the pressure is applied by revolving the screw-shaft.

Having thus described my invention, I claim—

1. In a wine or cider press, the combination of the piston and perforated piston-rod, provided with keys or pins, with the movable head, substantially as set forth.
2. In a wine or cider press, the screw-shaft *j*, gears *k*, and screws *l*, in combination with the movable head *n* and perforated rod *2*, provided with pins or keys *4*, substantially as shown and described.

In testimony that I claim the foregoing I have hereunto set my hand and seal this 2d day of December, 1873.

HORATIO N. HOUGHTON. [L. S.]

Witnesses:

NORTON P. OTIS,
JAMES M. TYLER.
